CLAIM

The ornamental design for a case for powered electric tool, as shown and described.

DESCRIPTION

FIG. 1 is a top, front, right perspective view of a case for powered electric tools showing my new design;

FIG. 2 is a left side elevational view thereof;

FIG. 3 is a rear elevational view thereof;

FIG. 4 is a top plan view thereof;

FIG. 5 is a bottom plan view thereof;

FIG. 6 is a front elevational view of a case for powered electric tools showing a second embodiment of my new design;

FIG. 7 is a left side elevational view thereof;

FIG. 8 is a top plan view thereof; and

FIG. 9 is a bottom plan view thereof.

FIG. 1.

FIG. 2.

FIG. 3.

FIG. 4.

FIG. 5.

FIG. 6.

FIG. 7.

FIG. 8.

FIG. 9.
